**OIL CATCHER AND DISCHARGER FOR
A VEHICLE**

William G. Colgan, Oakland, Calif.

Application November 4, 1957, Serial No. 694,288

7 Claims. (Cl. 184—106)

The present invention relates to improvements in an oil catcher and discharger for a vehicle; and it consists of the combinations, constructions and arrangement of parts, as hereinafter described and claimed. It has particular reference to improvements over the oil-catching receptacle with speed-controlled oil-discharger attachment for automobiles, as shown in my copending application Serial No. 584,016, filed in the United States Patent Office on May 10, 1956 (now Patent No. 2,841,245, dated July 1, 1958).

In the above-identified copending application, I disclose a receptacle that is adapted to be attached to the clutch pan of an automobile to catch dripping of oil. This oil is retained in the receptacle until the automobile has attained a predetermined speed at which time the accumulated oil is discharged onto the roadway. As illustrated therein, the receptacle defines a wind-tunnel passageway through which air will flow, as the automobile is advanced, with the air picking up the oil for discharge upon the roadway.

Although the device shown in the above-mentioned copending application is admirably adapted for use in the average climate, it has been found from practice that when it is used in cold climates, snow and moisture entering the wind-tunnel will freeze therein. This will prevent the discharge of the oil onto the roadway.

Accordingly, and as the principal object of the present invention, it is proposed to provide an all weather oil catcher and discharger for a vehicle. Briefly stated, it is proposed to utilize a swingably-mounted receptacle having a sump therein positioned to receive oil draining from the housing of a component of a vehicle power plant. This receptacle is swingable into a position to discharge accumulated oil therefrom onto the roadway. In order that the receptacle will be moved into oil-discharging position, it is provided with a portion against which wind will strike with sufficient force, when the vehicle has attained a predetermined speed, to swing the receptacle into a position to automatically discharge the accumulated oil. Until this speed has been attained, the receptacle is retained in a position to hold the oil.

Other objects and advantages will appear as the specification proceeds. The novel features will be set forth in the claims hereunto appended.

Drawings

For a better understanding of my invention, reference should be had to the accompanying drawing, forming part of this specification, in which:

Figure 1 is a longitudinal sectional view taken through a conventional clutch pan, and disclosing my oil catcher and discharger mounted therebeneath, parts being shown in section;

Figure 2 is a top plan view of the oil catcher and discharger; and

Figure 3 is a vertical transverse sectional view taken along the line III—III of Figure 1.

While I have shown only the preferred form of my

2

invention, it should be understood that various changes, or modifications, may be made within the scope of the annexed claims without departing from the spirit thereof.

Detailed description

Referring to the drawing, it will be noted that I have disclosed a conventional clutch pan A, which is fashioned with an outlet opening 10 in its lower wall 11. It is well known that a small quantity of oil B will accumulate in the bottom of the pan. Although the opening 10 is normally closed by a plug 12, some of the oil may leak out and will drop onto the garage floor, or upon the street when the automobile is parked. While I have specifically mentioned a clutch pan, it will be apparent that the same situation may apply to the housing of a component of a vehicle power plant.

My oil catcher and discharger is designated generally at C in the drawing. It includes a supporting frame D which may be secured beneath the pan or housing A by any suitable means so as to surround the opening 10. For this purpose, I have shown a plurality of permanent magnets 14 which are accommodated in grooves 15 fashioned in the upper surface of the supporting frame D and fixed to the latter.

Moreover, the oil catcher and discharger C includes a swingably-mounted receptacle E which is carried by the frame D, and having a sump E'. The latter is positioned to receive oil draining through the opening 10, thereby accumulating a body of oil B' in the sump. The receptacle E has horizontal trunnions 16 that are journalled in bearings 17 (see Figure 3). The latter are provided in a depending wall 18 forming part of the supporting frame D. Also, the supporting frame is provided with a drain chute D' that surrounds the opening 10. This drain chute is located to direct the oil from the opening 10 to the sump E' of the receptacle.

The direction of the forward movement of the vehicle is indicated by the arrow 19 in Figure 1. It will be apparent from the drawing that the depending wall 18 extends along both lateral sides of the receptacle E and across the trailing end of the latter, the forward end 18' of this wall being left open for the purpose hereinabove described, see Figure 1.

In its structural details, the receptacle E has an inclined bottom 20 and side walls 21. As clearly shown in Figure 3, the side walls 21 of the receptacle E are disposed inwardly relative to the opposite lateral depending wall 18 of the supporting frame D. Thus the depending wall 18 provides a protective shroud around part of the receptacle E, but leaving the forward portion 22 of the receptacle exposed to the wind, as suggested by the arrow 23 in Figure 1.

When the receptacle E is disposed in an oil-retaining position, as shown by the full lines in Figure 1, the deeper portion of the sump E' is disposed ahead of the trunnions 16, whereby the weight of the accumulated oil B' will tend to swing the receptacle into its oil-retaining position. Moreover, the receptacle is provided with a counterweight 24 ahead of the trunnions 16 so as to tend to depress the forward portion 22 of the receptacle.

After the vehicle has attained a predetermined speed, the wind 23 will strike the forward portion 22 of the receptacle with sufficient force to swing the receptacle E into the dot-dash line position shown in Figure 1. At this time, the accumulated oil B' will be discharged over the trailing end 25 of the receptacle onto the roadway. The swinging movement of the trailing end of the receptacle from its full-line position into its dot-dash line position is indicated by the arrow 26 in Figure 1.

It will be noted that the drain chute D' is disposed to constitute a limit stop, when the receptacle is swung in one direction about the trunnions 16 into an oil-retain-

ing position. The supporting frame D has a section 27 that is disposed to constitute a limit stop, when the receptacle E is swung in the opposite direction, that is, into an oil-discharging position.

The forward part of the supporting frame D is provided with a baffle 28, which extends transversely across the frame D, and this baffle is arranged to substantially preclude the wind 23 from gaining access to the sump E' of the receptacle. The forward portion 22 of the receptacle E defines a lip 29, which substantially contacts with the baffle 28 as the receptacle swings up and down.

Summary of operation

Assuming that the oil catcher and discharger C has been installed beneath the clutch pan A in the manner shown in Figure 1, the operations thereof may be briefly summarized as follows:

When the vehicle is parked or standing in a garage, any of the oil B in the bottom of this pan that may drip through the opening 10 will be directed by the drain chute D' into the sump E' of the swingably mounted receptacle E. This accumulated oil is designated at B'. The weight of the accumulated oil B' and the counterweight 24 will hold the receptacle E in the full-line position illustrated in Figure 1. Thus the accumulated oil B' will be prevented from draining onto the floor of the garage or onto the street.

However, as soon as the vehicle has attained a predetermined speed, the wind 23 striking the exposed forward portion 22 of the receptacle E will operate to lift the forward part of the receptacle and thus swing the receptacle into the dot-dash line position shown in Figure 1. At this time, the accumulated oil B' will be discharged over the trailing end 25 of the receptacle onto the roadway. Of course, when the vehicle slows down or is parked again, the receptacle E will automatically return to its oil-retaining position.

The lip 29 of the forward portion 22 of the receptacle E is protected by the baffle 28, when the force of the air has swung the receptacle into a position for draining the oil therefrom. This prevents ice, snow, water or mud from being scooped up by the receptacle, while the vehicle moves over the road. It is impossible, therefore, for the receptacle E to become clogged with foreign matter.

I claim:

1. In an oil catcher and discharger for a vehicle: a supporting frame mounted beneath an opening in a housing of a component of a vehicle power plant; and a swingably-mounted receptacle disposed within and being carried by said frame and having a sump positioned to receive oil draining through the opening in the housing; the receptacle being swingable into a position to discharge accumulated oil therefrom onto a roadway over which the vehicle may travel; the receptacle having an exposed forward portion against which wind will strike with sufficient force, when the vehicle has attained a predetermined speed, to swing the receptacle into oil-discharging position.

2. The oil catcher and discharger, as defined in claim 1; and in which the supporting frame defines a depending wall which is located to provide a protective shroud around part of the receptacle, but leaving said forward portion of the receptacle exposed to the wind.

3. The oil catcher and discharger, as defined in claim 2; and in which the forward part of the supporting frame is provided with a baffle that is arranged to substantially preclude the wind from gaining access to the sump of the receptacle.

4. In an oil catcher and discharger for a vehicle: a supporting frame mounted beneath an opening in a housing of a component of a vehicle power plant; and a swingably-mounted receptacle disposed within and being carried by said frame and having a sump positioned to receive oil draining through the opening in the housing; the receptacle being swingable into a position to discharge accumulated oil therefrom onto a roadway over which the vehicle may travel; the receptacle having an exposed forward portion against which wind will strike with sufficient force, when the vehicle has attained a predetermined speed, to swing the receptacle into oil-discharging position; the supporting frame being provided with a drain chute, which surrounds the opening in the housing; the drain chute being located to direct the oil from said opening to the sump of the receptacle; the drain chute being disposed to constitute a limit stop, when the receptacle is swung in one direction; and the supporting frame having a section disposed to constitute a limit stop, when the receptacle is swung in the opposite direction.

5. In an oil catcher and discharger for a vehicle: a supporting frame mounted beneath an opening provided in a housing of a component of a vehicle power plant; a receptacle disposed within said frame and having horizontal trunnions journaled in the supporting frame; the receptacle having an inclined bottom defining a sump; the sump being positioned to receive oil draining through an opening in the housing; the receptacle having a deeper portion which is disposed ahead of the trunnions, whereby the weight of the accumulated oil therein will tend to swing the receptacle into oil-retaining position; the receptacle being swingable on the trunnions into a position to discharge the accumulated oil over a trailing end of the receptacle onto a roadway over which the vehicle may travel; the receptacle having a forward portion against which wind will strike with sufficient force, when the vehicle has attained a predetermined speed, to lift the forward part of the receptacle and swing the receptacle into oil discharging position.

6. The oil catcher and discharger for a vehicle, as defined in claim 5; and in which the receptacle is provided with a counterweight forward of the trunnions that is disposed to urge the receptacle into oil-retaining position.

7. The oil catcher and discharger, as defined in claim 5; and in which the forward part of the supporting frame is provided with a depending baffle that overlaps the forward portion of the receptacle sufficiently at all times to preclude ice, snow, water or mud from being scooped up by the receptacle, while the vehicle moves forwardly over the roadway.
